UNITED STATES PATENT OFFICE.

JOHN V. GODDARD, OF TRENTHAM, ENGLAND, ASSIGNOR TO HUGH C. EDMISTON, OF NEW YORK, N. Y.

DESIGN FOR A PLATE OR SIMILAR ARTICLE.

Application filed January 17, 1929. Serial No. 29,654. Term of patent 7 years.

To all whom it may concern:

Be it known that I, JOHN V. GODDARD, a subject of the King of Great Britain, residing at Trentham, county of Stafford, England, have invented a new, original, and ornamental Design for a Plate or Similar Article, of which the following is a specification, reference being had to the accompanying drawing, forming part thereof.

Figure 1 is a plan view of a plate showing my new design, a portion being shown broken away, it being understood that the remainder is a mere repeat of the ornamentation shown. Figure 2 is a side elevation of the same.

I claim:

The ornamental design for a plate or similar article as shown and described.

JOHN V. GODDARD.
